UNITED STATES PATENT OFFICE.

WALTER WRIGHT, OF NEW YORK, N. Y.

TYPE-SETTING MACHINE.

1.300.089.

Specification of Letters Patent.

Patented Apr. 8, 1919.

Application filed August 10, 1912, Serial No. 714,330. Renewed September 13, 1918. Serial No. 253,985.

To all whom it may concern:

Be it known that I, WALTER WRIGHT, a citizen of the United States, and a resident of the city of New York, county and State 5 of the same name, have invented certain new and useful Improvements in Type-Setting Machines, of which the following is a specification.

This invention is in the nature of an improvement on the type of typesetting machine described in my prior application, Serial No. 629,394, filed May 25, 1911, looking toward the enlargement of the capacity and efficiency of that machine.

10 Its objects are, first, to provide a mechanism in which each key controls two separate type characters through selective operating devices.

Second, to arrange the machine so as to 20 provide for the application of power to hand manipulation.

Third, to provide means whereby different sizes or styles of type fonts can be used in the same structure.

25 Fourth, to provide a mechanism capable of being actuated up to the full speed limit of the operator.

These and other objects, such as simplicity, economy of space and power required, 30 ease and positiveness of operation, are attained by the novel construction and combination of parts hereinafter fully described and shown in the accompanying drawings, forming part of this specification, and in 35 which:—

Figure 1 is a partial side elevation and vertical section of an embodiment of the invention, showing the general arrangement of the operative parts.

40 Fig. 2 is a general plan view of the same.

Fig. 3 is a perspective view showing the key-lever and shift arrangement.

Fig. 4 is a partial plan view, showing the application of power to the key levers.

45 Fig. 5 is a side view of the same, showing the levers in normal position.

Fig. 6 is a perspective detail of the shift catch.

Fig. 7 is a view similar to that of Fig. 5, 50 but showing a key lever depressed, as in operation, and a rotative hook member engaged therewith.

Fig. 8 is an enlarged detail view of a key-lever cam and its connections.

55 Fig. 9 is a perspective detail of the type outlet or mouth piece.

Fig. 10 is a perspective detail of the type conveying channel tube.

Fig. 11 is a partial plan view of means for preventing the simultaneous operation 60 of two keys.

Fig. 12 is a transverse section of the same, taken on line 12—12 of Fig. 11.

Fig. 13 is an enlarged sectional view of the type bed and carrier, taken on line 65 13—13 of Fig. 2.

Fig. 14 is a similar cross section showing the same and allied operative mechanism, taken on line 14—14 of Fig. 2, and,

Fig. 15 is a perspective view of the shift 70 keys and locking mechanism.

The drawings illustrate an embodiment of the invention designed particularly to operate on a type supply contained in a cylindrical magazine or grooved drum 75 wherein the different characters of type are arranged in separate vertical columns, radially disposed with the faces extending outwardly, the lowermost type in each row resting upon a flat surface below the magazine. 80

Over this surface, in register with each column, are ejectors operatively connected in such manner as to engage with any selected individual type, advancing it radially outward from the magazine directly 85 into the path of a rapidly rotating annular carrier, traveling concentric to the magazine over the flat surface upon which the type rest, and forming therewith a type-race.

At a single point in the path of travel of the carrier is an outlet common to all of the type, conforming to their contour and having a raised barrier at its far side preventing further forward movement or over- 95 carriage of type.

Combined with the carrier are a plurality of yieldingly mounted plungers, which in passing over the type at the barrier press downward so as to eject it through the outlet 100 into a conveyer which delivers the same, by gravity, to a chase or other assembling device with which it communicates.

The carrier is formed with a narrow annular ridge on its under side adapted to engage with a groove in the type and is arranged so as to be raised a limited amount coincident with the projection of a type into its path, immediately descending until the ridge enters the type groove holding it in 110 position in conjunction with the ejector until the yielding plungers contact with the edges

and carry it to the outlet; it is further provided with means for ready removal in order to obtain access to the flat surface over which the type moves.

5 The arrangement is such that when a character key is depressed a corresponding type will be ejected from the magazine, the carrier slightly raised to permit entrance of the type into its path and then lowered, the 10 type carried thereby to the outlet, and forced through into the channel leading to the chase, while the ejector and key are restored to their normal position.

The invention, more specifically described, 15 comprises a cylindrical magazine 20 having a plurality of T shaped slots 21 in its periphery corresponding to the number of characters it is desired to use; in the slots, which are arranged radially, are columns 20 of type 22, each slot being appropriated to a certain character; all of the type face outwardly, flat side down, the lower-most resting directly on a smooth, flat bed 23 disposed annularly below the magazine 20 25 which it supports through the ring 26 on which is the rim 37 of the lower magazine spider, 38 a similar spider being at the top of the magazine.

The ring 26 has an inwardly extending rib 30 27 formed with an open groove 28 at the upper side through which are a series of cuts so made as to form individual brackets or supports 30 for the bell-cranks 31 which have a short pivot 32 resting in the groove 35 and maintained therein by a cover-plate 33; above this cover-plate are a series of pins 34 to which are attached one end of the springs 35, the other being connected with the inwardly extending arm of the bell- 40 crank 31, the extreme inner end of which is pivotally attached to the upper end of links 36.

The opposite arm of the bell-crank 31 is 45 connected to the push bar or ejector 40 operable in straight radial lines on the surface of the bed 23 being guided by slots formed in the bottom of the ring 26.

Around the outer edge of the bed 23 is 50 a raised flange 24 which limits the outward movement of the type, the bed being supported by the cylindrical base 25.

A traveler 42, mounted concentric to the flat annular base 23, and provided with a ridge 43 adapted to engage with a groove 55 formed laterally across the upper surface of the type, is removably connected with a ring 47 surrounding the base 25 by means of slotted openings fitting studs 45, the heads of which may pass freely through enlargements formed opposite to the driving end of the slots in such manner as to permit the traveler to be removed when desired.

The ring 47 has a circumferential groove 60 near its lower edge forming a race-way for

the balls 48, the other race being in the vertical movable annulus 50; it will be noticeable that the ball races are so formed as to permit the ring 47 to revolve and also that the balls lock the ring to the lower member against any other movement.

Another groove is also formed around the ring 47 to receive the belt 51 which conveys rotary motion to it from the motor 52, the belt running from the pulley 53 over the idlers 55 and 56 mounted on brackets at the 75 rear of the machine.

The vertically movable annulus 50 is engaged with the base 23 by means of balls 60 set partially in indentations formed in the inner side of the annulus and partially in vertical elongated slots 61 formed in the periphery of the base at intervals around its circumference in such manner that the annulus is free to move up or down a limited distance with relation to the base, but cannot 85 revolve about it.

A number of pins 62, preferably three, set in the exterior of the annulus, at equidistant points are engaged with links 63 extending from the levers 64 secured on 90 the shafts 65 turning in brackets 66 and 67.

These shafts are connected, as at 68, to work in unison and have upon them other levers 69 extending outwardly and connecting with vertical links 70 attached at their 95 lower ends to horizontal levers 71 fulcrumed at their outer ends, their opposite ends being adapted to engage with the vertical hook lever 72 pivotally mounted on levers 73 operated by all the character keys through 100 a universal bar 75; the lower ends of the hook lever are beveled or cam shaped to engage with a fixed pin 76 in such manner as to disengage the hook end when the key levers have been depressed a definite distance.

From the foregoing it will be seen that whenever a character or space key is depressed that the traveler 42 is caused to be raised sufficiently to allow a type to be projected into its path by an ejector whereupon the traveler is instantly lowered so that the ridge 43 engages with the groove in the upper surface of the type.

In register with the ridge 43 are a series 115 of vertically mounted pins 78 extending through the traveler and contained in housings 79 secured on its upper surface, the pin being pressed downwardly by the compression spring 80 in such manner that its 120 rounded point is adapted to make contact against one of the grooves formed in the edges of the type, causing it to advance in a circular path.

At a single point in the path of the type-travel is an outlet or mouth-piece 82 interchangeably held in relation to the flat base 23 by means of the screw 83; these outlets,

which are made to conform to the size and shape of type used, are provided with a raised front lip 84 in register with the flange 24 and have correspondingly raised walls at 5 its inner end 85 and along the far side 86 acting as an abutment against which the incoming type strike, forcibly detaining them, while the spring pins 78 ride over the type 10 pushing them downwardly through the opening, without damage; it will be understood that the near or incoming wall of the outlet is in the same plane as the bed surface so that no impediment is offered to incoming type which are guided in their 15 descent through the outlet by projections 87 and 88 the same being suited to the edge grooves formed in the type.

Below and in register with the outlet 82 is a tubular conveyer 90 having an open slotted 20 front through which the face of the type extend, while the body is contained within, the edges of the slotted portion engaging with the grooves in the edges of the type which drop by gravity to a chase or other suitable 25 receptacle with which the tube communicates.

A plate 91 is secured to the tube and is provided with openings 92 extending inwardly on opposite sides in such manner as 30 to engage with a screw or the like, by partially turning the tube, the same forming an adaption of the well known bayonet-joint lock.

At the front of the machine is a key-board 35 preferably arranged in a manner similar to that of a standard type-writing machine, having keys 100 upon levers 101 which extend rearwardly being fulcrumed at their ends to a common axis 102 and have compression return springs 103 or equivalent devices for the purpose.

Below all the key levers pass the universal bar 75, the function of which, with reference to the traveler, has heretofore been 45 described.

Midway in each character key lever 101, in a vertical plane, corresponding to the center of the magazine, is a pivoted shift-hook 105 having engaging points 106 at its extreme upper ends and a slot 107 extending downward centrally therebetween.

These hooks are adapted to swing or oscillate on the pivoted connection with the levers, forward and back so as to engage with 55 the indent ends 37' of the links 36, the latter having a rectilinear motion through a pair of guides 48' which are secured parallel to each other, at their ends on opposite sides of the machine.

Disposed in the slots 107 and engaging with all the shift hooks, is a rod 108 extending from side to side having its end connected with the vertical arm 109 of the bell-crank levers, pivoted at 110 on brackets

attached to the machine frame; the other 65 horizontally disposed arms 111 are connected to links 112, the opposite end of which is attached to the shift key levers 115 in such manner that when either of the shift keys are depressed the rod 108 is carried 70 rearwardly rocking all of the shift hooks so that they are in position to engage with the back row of links 36, arranged to operate the ejectors around the rear of the magazine, which portion contains preferably upper 75 case type or the less frequently used characters, while the front contains lower case type embracing more commonly used characters.

It will be understood from the foregoing that each key controls two characters, both 80 upper and lower case and that the operation of selection is accomplished through the shift keys which move in unison as usual; when it is desired to use upper case type singly or in a limited number the left hand 85 shift key is preferably depressed, as upon its release lower case type are instantly brought into the field of action of the character keys; but if upper case type are desired in any considerable quantity the right 90 hand shift key may be depressed thereby operating the hook 119 which is secured to the through rod 116, the hook engaging automatically with pins 117 set in the shift levers through the springs 118 but which 95 may be disengaged by pressure on the knob 119 whereupon the shift hooks swing forward delivering lower case type exclusively while in this position.

At a uniform point, near the front end of 100 each key lever 101 are pivotally attached dependent links 130 having at their lower ends pins 131 projecting outwardly at both sides; closely adjacent to the links are plates 132 having cam grooves 133 formed in the side 105 next the links and which engage with the pins 131 in such manner that when any key is depressed the pin in the link attached to that lever is caused to travel a circuitous path, this effect being obtained partially by 110 the springs 134 which tend to draw the links rearwardly so that the pin passes over the center of the cam into position to move down the angular inner surface toward the rear as the key is depressed.

This rearward and downward motion of the pins 131 brings them within the path of revolution of rapidly revolving hook disks 135 mounted on a shaft 136 and driven by a pulley 137 through the belt 138 running 120 over an idler 139 from the driving pulley 140 on the motor 52.

This arrangement is such that when that portion of the pin on the other side of the link is engaged by the hook disk it is carried 125 down the full length of the cam groove—which corresponds with the key lever action—and discharged past the angular inner

point of the cam groove in such manner as to be carried freely up on the opposite side by the key lever spring into position for another stroke.

5 While the hook disk is shown with two engaging faces, it may be made with one or any preferred number; in order to prevent a pin being caught inopportune the plates 132 are mounted yielding by means of a pin 142 set rigidly in the reduced lower end 143, the pin working in a curved slot 144 formed in horizontally disposed levers 145 fulcrumed on a rod 146 common to all, each of the levers having independent pull springs 147 at their opposite ends, the curved slot being midway between; the plates are maintained in a vertical position by means of a rod 148 which passes through an elongated slot 149 formed in the plates between the 10 cam groove 133 and the pin 142; also on this rod are collars which serve as distance pieces between the cam plates.

From the foregoing it will be seen that whenever a key is depressed, even a slight 25 distance, it is carried by power through its full stroke and a complete operation performed independent of the operator who has but to merely start the key in its initial movement.

30 Means for preventing the simultaneous depression of two or more keys are provided for by the device shown in Figs. 11 and 12 wherein a rod 155 is shown passing across the machine above the key levers; 35 from this rod depend a plurality of loosely mounted members 156 having between them on the rod, collars 157 and provided with enlarged lower ends 158 immediately below the body of the key levers.

40 These members may be of circular cross section having spatulate ends, and are maintained in alinement by other rods 159 affixed in the machine frame.

45 It will be understood that the members 156 are confined at the ends of the row in such manner that the extreme outer members cannot move outwardly; also that the spatulate ends are of uniform breadth, the combined flattened ends filling the space between the confines so fully that there is 50 room for only one of the key levers to pass between, consequently two key levers cannot be depressed at the same time although one may be, and at any point, the members 55 swaying sidewise all being in intimate contact when the lever is depressed.

The complete embodiment of the invention comprises a suitable frame work, type receiving devices and means for operation 60 thereof and in every respect a practical working structure the operation of which has been hitherto explained in detail so that it will be clearly understood by those familiar with the art without further description.

Having thus described my invention what I claim as new and desire to secure by Letters Patent is:—

1. In a type setting machine, a series of upright type supply channels, a type race 70 at the lower ends of said channels comprising a rotary type-pushing member, and an ejector for each channel adapted to discharge type therefrom to the race, in combination with a set of key levers less in number than the ejectors, operating connections from each lever comprising a part adapted for alternate connection with two ejectors and a shift key for selecting the connection made by said part.

2. In a type setting machine having gravity type-supply channels, a type-race comprising a rotary type-pushing member and ejectors for each channel, the combination of two of said ejectors, a single key for actuating either of them, a shift catch forming part of the line of operating connections between said key and each ejector, and a shift key for swinging said catch from connection with one ejector or the other.

3. In a type setting machine of the kind described, having, gravity type-supply channels, a type race with a rotary type pushing member and a series of key levers less than the supply channels, the combination of ejectors for each channel, a shift catch carried by each key lever and a shift key for shifting said catch into operating connection with either of two of said ejectors.

4. In a type setting machine having a circular set of gravity supply channels and ejectors therefor, the combination of a set of key levers, less in number than the supply channels, with means combined with said levers whereby either of two substantially diametrically disposed ejectors may be operated thereby.

5. In a type setting machine of the kind described, a set of key levers and power means for imparting full throw thereto comprising cam-plates 132 and pins connected to said levers and cam-plates.

6. In a key operated type-setting machine, the combination with a key-board comprised of spring returnable key levers and means for operation thereof, of hook members pivotally connected with the key levers, a revolving element below the said key levers adapted to engage with said hook members and means for causing said hook members to travel circuitously in and out of the path of rotation of said revolving element whereby the partial downward movement of any key lever causes interengagement between the said hook member and the said revolving element.

7. In a type setting machine, in combination with a magazine and means of type delivery therefrom, of a flat annular base ex-

tending beyond said magazine adapted to receive the delivered type, an outlet suited to the type used, removably secured in said base, said outlet being provided with 5 raised portions adapted to intercept type and means for advancing delivered type to said outlet.

8. In a machine of the class described, in combination with the key levers, of bars 10 pivotally depending therefrom having projections at their extremities, cam plates for each bar having slots so formed as to cause said projections to travel circuitously when depressed, rotating hook disks mounted adjacently to said cam plates in such manner as to engage with said projections when on 15 their downward course in said cam plates causing them to complete their circuit therein, yielding supports for said cam plates 20 whereby the latter may move outwardly and downwardly from said hook disks and means for returning them to a normal position.

9. In a machine of the class described, in combination with the key levers, of arms 25 pivotally connected to each lever, hook elements mounted to revolve contiguous to said arms, and yieldingly mounted cams engaging said arms adapted to cause them 30 to move out of a vertical plane when the levers are depressed and into the path of rotation of said hook elements, whereby said arms are caused to engage with the hook and complete a full downward stroke before 35 returning to a normal position, said cams holding said arms away from said hook elements during their return movement.

10. In a type-setting machine, in combination with means for ejecting type outwardly from a magazine and a circular race-way upon which type may be ejected, of a rotatable member having on its under 40 side a rib adapted to act as a key for engaging with ejected type at a predetermined point in their ejection, a source of power for constantly rotating said rotatable member and means combined with said power source for raising said rotatable 45 member and for causing the ejection of type.

11. In a key operated type-setting machine, in combination with a cylindrical magazine, ejectors at the bottom of the channels thereof, bell-crank levers operatively 50 engaging said ejectors, and a plurality of key levers including a shift key lever, of in-turned hook links depending from said bell-crank levers, guides through which said links move rectilinearly, said guides being 55 oppositely disposed, double ended pawl members pivoted to said key levers, said members registering with said links and means combined with the shift key lever for 60

shifting said double ended pawl members into operative engagement with either of its 65 corresponding hook links.

12. In a key operated type-setting machine the combination with a cylindrical magazine, ejectors at the bottom of the channels thereof, bell-crank levers operatively 70 engaging said ejectors, and a plurality of key levers, of hook links depending from said bell-crank levers, guides for said links and shiftable means for selectively connecting said key levers to said links. 75

13. In a rotary type setting machine, the combination with the magazine of supply channels, a circular type race comprising a ring-form type-transferring member, a support on which such member is removably 80 mounted, and means for rotating said support and with it the said member.

14. In a type setting machine, the combination with a magazine of type-supply channels with ejectors, a type-race common 85 to all of said channels and provided with a power driven type-pusher, of a series of keys each adapted to cause delivery of a type into said race and means whereby the operation of one key automatically locks adjacent keys from operation. 90

15. In a type setting machine the combination with a type-race comprising a smooth bed and overlying type-pusher, of a throat suited to the contour of the type used and 95 removably secured to said bed in the path of the type moving thereon, and a delivery chute forming a continuation of said passage and adapted to conduct the type to the point of composition. 100

16. In a type setting machine, a type-race comprising a smooth bed on which the type move and an overlying pusher for said type, a throat secured to said bed to intercept the type moving thereon and a discharge chute connecting with said throat, said throat and chute being both removable from the machine to accommodate the same to different forms of type. 105

17. A type setting machine, comprising 110 a type magazine, a type race comprising a type pusher, a discharge throat and chute, a chase to receive the selected type therefrom, and a set of operating keys adapted to eject the type into said race, said chase being 115 faced away from the set of operating keys and below said magazine to receive the type by gravity from said chute.

In testimony whereof I have signed my name to this specification in the presence of 120 two subscribing witnesses.
